UNITED STATES PATENT OFFICE.

JOSEPH B. LAUGHTON, OF WESTFIELD, MASSACHUSETTS.

INKING-PAD.

SPECIFICATION forming part of Letters Patent No. 710,699, dated October 7, 1902.

Application filed December 26, 1901. Serial No. 87,145. (No model.)

To all whom it may concern:

Be it known that I, JOSEPH B. LAUGHTON, a citizen of the United States of America, and a resident of Westfield, in the county of 5 Hampden and State of Massachusetts, have invented certain new and useful Improvements in Inking-Pads, of which the following is a full, clear, and exact description.

This invention relates to improvements in 10 inking-pads and holders or containers therefor.

The invention comprises a shallow box or 15 tray having hinged thereto at the rear edge thereof a rectangular frame adapted to be swung open rearwardly away from and closed over upon the top of the box in the manner of a hinged box-cover and having an inking-pad journaled at its opposite ends centrally within said rectangular frame and adapted 20 when the frame is swung open to have an overturning movement within the frame, so that when the frame is again placed in its closed position on and above the upper edge of the box the surface of the inking-pad may 25 be uppermost and outermost and in presentation for inking a rubber stamp, or the back of the pad or the sheath or container therefor may be uppermost, the inverted pad being inclosed and protected within the box; 30 and the invention furthermore comprises a handle or thumb-piece formed as an extension of one of the journals for the reversible pad located beyond the ends of the hinged frame, by means of which with the thumb 35 and finger the pad may be reversed without directly touching it to soil or smutch the finger; and the invention furthermore comprises in the appliances as first above characterized the arrangement of rests or ledges at the ends 40 of the box, located within the ends of the container or support for the pad proper, so that the pad may have ample support on said rests to be immovably sustained for receiving the impact thereupon of the stamp to be inked. 45 The improved inking-pad is fully and clearly illustrated in the accompanying drawings, in which—

Figure 1 is a perspective view showing the hinged frame as swung upwardly from the 50 box to permit the swinging and overturning action therewithin of the pad and its container. Fig. 2 is a longitudinal section of the

device, the swinging frame being shown as swung down to its closed position upon the top of the box and showing the inking-pad 55 with its inking-surface uppermost. Fig. 3 is a cross-sectional view taken on the line 3 3 of Fig. 2, the pad being, however, shown as inverted and inclosed within the box and having its lower surface in contact against an 60 ink-replenishing absorbent layer located in the bottom of the box.

Similar characters of reference indicate corresponding parts in all of the views.

In the drawings, A represents the box or 65 tray, of rectangular form, having in its bottom a layer *a* of felt or other absorbent material susceptible of having incorporated therein the inking material for supplying and replenishing the pad B.

C represents a rectangular frame in external size corresponding substantially to that of the box, and said frame is at its rear longitudinal edge at *b* hinged at and along the rear edge of the box, a cloth hinge being suitable for such connection. It will be noticed that the end members *d d* of the frame are comparatively thin or narrow and that the rests or supports *ff* at and within both ends of the box when the frame is swung down on 80 the upper edge of the box have their locations within the frame end members *d*.

The pad B has its bottom and edges inclosed within the pad container or sheath *f* which may advantageously be a shallow sheet-metal tray or pan, the inking-face of the pad expanding above the open top of the container, and the said container has at its ends outside of the ends of the pad the portions *g g* to be supported on the aforementioned 90 rests *ff* of the box to give steady and stable support to the pad.

The pad is pivoted in its central longitudinal line within the center of the frame C, and one of the pintles or journal-rods projects endwise outwardly beyond the frame and has the handle *i*, which when grasped by the thumb and fingers affords means for easily rotating the pad-container and pad within the frame.

As shown in Fig. 2, the handle-provided journal-rod has its stem or shank passed loosely through a perforation *j* therefor in the frame and penetrates by a tight driving

fit the material composing the pad-container and the pad-base, so that by positively rotating the journal-rod the container and pad will be turned as one therewith.

5 The parts *f* and *g*, shown in the drawings as strips secured in their appropriate places within the ends of the box and the pad-container outwardly beyond the ends of the pad, might integrally be formed with the box and 10 container.

Having thus described my invention, what I claim, and desire to secure by Letters Patent, is—

1. The combination of a box; a frame 15 hinged to the box; an ink-pad journaled in the frame; means other than the journals for supporting the ink-pad in the box with the inking-face uppermost and its reverse side free from the bottom of the box; the frame and ink- 20 pad being arranged to permit the inking-face to engage the bottom of the box.

2. The box of rectangular form having at its opposite ends the rests *ff* combined with the rectangular frame at its rear longitudinal 25 edge hinge-connected to the corresponding edge of the box, and having its end members

d d arranged outside of the inner edges of said rests *ff*, and the pad pivotally supported within and in the central longitudinal line of said frame, and adapted when the frame 30 is swung to its closed position, to have the end portions of such pad supported upon said rests, substantially as described.

3. Inking-pad devices consisting of the rectangular box, the rectangular frame hinge-connected at one edge to the box, and the pad arranged within the frame and having journal members by which the pad is pivotally and reversibly supported within the frame, one of said journal members passing loosely through 40 a perforation therefor in the frame, and with a driving fit or engaging connection into the pad, and having its outer end portion extended beyond the frame, and provided with a handle, substantially as described. 45

Signed by me at Springfield, Massachusetts, in presence of two subscribing witnesses.

JOSEPH B. LAUGHTON.
